UNITED STATES PATENT OFFICE.

JAMES CROXON METCALFE AND RICHARD DAVID METCALFE, OF FALLOWFIELD,
ENGLAND.

INJECTOR.

No. 905,206.

Specification of Letters Patent.

Patented Dec. 1, 1908.

Application filed May 10, 1907. Serial No. 372,951.

To all whom it may concern:

Be it known that we, JAMES CROXON METCALFE and RICHARD DAVID METCALFE, subjects of the King of Great Britain and Ireland, residing at Sheen Bank, Lord street, Fallowfield, in the county of Lancaster, England, have invented certain new and useful Improvements in Injectors, of which the following is a specification.

This invention relates to injectors and has for its object to produce an injector capable of dealing with high pressure steam and hot feed water and of automatically starting and re-starting itself.

Heretofore injectors have been provided with an overflow valve controlled by the pressure in the delivery chamber of the injector, but with such injectors difficulty has been experienced owing to the pressure in the overflow chamber breaking the jet passing through the combining nozzle at its inlet end, and to the overflow valve preventing that free escape of steam when the injector is starting, or when the jet breaks, which is essential to the automatic starting and re-starting of the appliance. The latter defect is due to the steam, when the injector is starting, setting up a pressure in the delivery chamber of the injector and so holding the overflow valve on its seat.

The invention comprises the improved combinations and arrangements of parts hereinafter described and claimed whereby the aforesaid defects are overcome.

Referring to the four accompanying sheets of explanatory drawings;—Figure 1 is a part sectional elevation and Fig. 2 a part sectional plan of an injector constructed in one convenient form according to our invention. Figs. 3 and 4 are similar views to Figs. 1 and 2 respectively, showing a modified form of our injector. Figs. 5 and 6 show in sectional elevations further modified forms of our injector.

The same reference letters in the different views indicate the same or similar parts.

In Figs. 1 and 2, *a* is the forcing steam nozzle of the injector, *b* the lifting steam nozzle and *c* the combining nozzle. The lifting steam nozzle *b* is so proportioned and arranged with respect to the inlet end of the combining nozzle *c* as to produce a suction action in the feed water pipe in the well known manner.

The entering feed water is caused to sur-

round the steam jet in a thin annular film moving with a very high velocity. When the injector is working normally it is found that a vacuum or partial vacuum exists at a point between the ends of the lifting and forcing steam nozzles *b* and *a* respectively, but that a pressure exists beyond the forcing steam nozzle. We therefore provide a means of communication *m* between the interior of the combining nozzle *c* and the overflow chamber at a point between the ends of the lifting and forcing steam nozzles to allow of the escape of the steam from the lifting nozzle when starting and to permit of the introduction of a supplementary supply of water, as hereinafter described. For preventing the pressure beyond the forcing nozzle passing by way of the overflow chamber to the inlet end of the combining nozzle where the slot or gap *m* is situated and so destroying the vacuum at that point and breaking the jet, we divide the overflow chamber into two independent compartments *f*, *g*, each fitted with its own overflow valve as *d* and *e* respectively.

h is the common overflow passage.

When the steam is of high pressure and the feed water of high temperature, the pressure in the chamber *f* rises very considerably, while we find that a very high vacuum exists in the compartment *g* throughout the normal working of the injector. We therefore provide a valve for the compartment *f* which during the normal working of the injector is loaded, but when the injector is starting is only partially loaded to permit of the release of any excess pressure in *f*. The automatic loading is effected by means of the plunger *i* through the medium of the lever *j*, the plunger *i* being acted on by the pressure in the discharge chamber of the injector. The other compartment, namely *g*, is quite unaffected by the conditions existing in the compartment *f* and is fitted with a free valve *e* which can allow of the escape of any pressure which may exist in *g*, as for example when the injector is starting though no delivery is taking place therefrom, or when the jet in the nozzle *c* breaks. Such valve *e* also prevents the inflow of air when the injector is working normally and a vacuum exists in *g* as before described.

By the employment of a free valve on an independent compartment as *g* containing the first slot or gap *m*, situated between the

- ends of the lifting and forcing steam nozzles, the injector is rendered capable of quickly clearing itself of steam for starting and restarting purposes, and the employment of 5 automatic controlling means for the valve d and a supplementary water inlet to the compartment g renders the injector capable of automatically dealing with hot feed water and high pressure steam.
- 10 We preferably place an ordinary opening flap n on a portion of the combining nozzle at the inlet end of the compartment f so that the pressure at the slot or gap o at the delivery end of such compartment, which pressure 15 is greater than that at n , cannot obtain access to the combining nozzle at n during the working of the injector, while the said flap n opens when the injector is starting and permits steam to freely escape from the combining nozzle.
- The water valve p opens into the compartment g under the suction action of the jet passing through the combining nozzle c to permit of the inflow of a supplementary supply 25 of water to said jet. Such supplementary supply of water acts to cool the jet and reduce the pressure in the compartment f during the working of the apparatus.
- In the arrangement shown in Figs. 3 and 30 4, instead of employing a slot as m (Figs. 1 and 2) in the portion of the combining nozzle in the compartment g , we employ a flap as r , or, if desired, we may employ a combination of a slot and flap with or without the 35 water inlet controlled by the valve p .
- If desired we may arrange the overflow valve e to communicate direct with the atmosphere instead of with the common overflow passage h .
- 40 Instead of an opening flap as n in the portion of the combining nozzle in the compartment f , we may employ an additional slot or gap s as shown in Fig. 5, or a sliding nozzle t as shown in Fig. 6. The said sliding nozzle 45 is provided with wings u for supporting and guiding it within the extension v of the discharge cone w . The sliding nozzle is also formed with a projecting portion or flange x adapted, when the nozzle is in the position 50 shown, to seat upon the annular extension y of the combining nozzle c . The action is as follows;—when the injector is starting, the pressure of the steam forces the sliding nozzle t towards the discharge end of the injector and so provides a passage between the 55 parts x and y for the free escape of steam and water. When the injector is working normally, the sliding nozzle t is forced, by the pressure at the delivery end of the combining nozzle, towards the inlet end of the injector and a joint is thus made between the parts x and y , so that the pressure in the 60 chamber f shall not affect the jet passing through the combining nozzle at this point.
- 65 Having now described our invention, what we claim as new and desire to secure by Letters Patent is;—
1. In injectors, in combination, lifting and forcing steam inlet nozzles, a combining nozzle, co-axial with said lifting and forcing nozzles, an overflow chamber divided into independent compartments surrounding said combining nozzle, communicating means between the interior of said combining nozzle at a point between the ends of 70 said lifting and forcing steam nozzles and the first compartment of the overflow chamber, communicating means between said combining nozzle and the other of said compartments of the overflow chamber, an overflow passage, a valve way or passage, for each of said compartments, independently communicating with said overflow passage, a free overflow valve in the said valve way or passage of the compartment at the inlet 75 end of the combining nozzle, and a valve automatically loaded during the normal working of the injector in the valve way or passage at the delivery end of the combining nozzle, substantially as set forth. 80
2. In injectors, in combination, lifting and forcing steam inlet nozzles, a combining nozzle co-axial with said lifting and forcing nozzles, an overflow chamber divided into independent compartments surrounding said 85 combining nozzle, communicating means between the interior of said combining nozzle at a point between the ends of said lifting and forcing steam nozzles and the first compartment of the overflow chamber, communicating means between said combining nozzle and the other of said compartments of the overflow chamber, an overflow passage, a valve way or passage, for each of said compartments, independently communicating with said overflow passage, a valve 90 automatically loaded during the normal working of the injector in the valve way or passage at the delivery end of the combining nozzle, substantially as set forth. 95
3. In injectors, in combination, lifting and forcing steam inlet nozzles, a combining nozzle co-axial with said lifting and forcing nozzles, an overflow chamber divided into independent compartments surrounding said combining nozzle, communicating means between the interior of said combining nozzle at a point between the ends of said lifting and forcing steam nozzles and the first compartment of the overflow chamber, communicating means between said combining nozzle and the other of said compartments of the overflow chamber, an overflow passage, a valve way or passage, for each of said compartments, independently communicating with said overflow passage, a discharge chamber to the injector, a free overflow valve in the valve way or passage of the compartment at the inlet end of the combining nozzle and a valve, automatically 100 loaded during the normal working of the injector by the pressure in said discharge chamber, in the valve way or passage of the compartment at the delivery end of the combining nozzle, substantially as set forth. 105
3. In injectors, in combination, lifting and forcing steam inlet nozzles, a combining nozzle co-axial with said lifting and forcing nozzles, an overflow chamber divided into independent compartments surrounding said combining nozzle, communicating means between the interior of said combining nozzle at a point between the ends of said lifting and forcing steam nozzles and the first compartment of the overflow chamber, communicating means between said combining nozzle and the other of said compartments of the overflow chamber, an overflow passage, a valve way or passage, for each of said compartments, in- 110
- 115
- 120
- 125
- 130

dependently communicating with said overflow passage, a discharge chamber to the injector, a free overflow valve in the valve way or passage of the compartment at the 5 inlet end of the combining nozzle, a valve, automatically loaded during the normal working of the injector by the pressure in said discharge chamber in the valve way or passage of the compartment at the delivery 10 end of the combining nozzle, and a water inlet valve to the compartment at the inlet end of the combining nozzle, substantially as set forth.

4. In injectors, in combination, lifting 15 and forcing steam inlet nozzles, a combining nozzle co-axial with said lifting and forcing nozzles, an overflow chamber divided into independent compartments surrounding said combining nozzle, communicating means between the interior of said combining nozzle at a point between the ends of said lifting and forcing steam nozzles and the first compartment of said overflow chamber, opening and closing means of communication between the interior of said combining nozzle

and the inlet end of the other compartment and a gap forming means of communication between the interior of the combining nozzle and the outlet end of said compartment, an overflow passage, a valve way or passage, 30 for each of said compartments, independently communicating with said overflow passage, a discharge chamber to the injector, a free overflow valve in the valve way or passage of the compartment at the inlet end of 35 the combining nozzle, a valve, automatically loaded during the normal working of the injector by the pressure in said discharge chamber, in the valve way or passage of the compartment at the delivery end of the 40 combining nozzle, and a water inlet valve to the compartment at the inlet end of the combining nozzle, substantially as set forth.

In testimony whereof we affix our signatures in presence of two witnesses.
